[57] CLAIM

The ornamental design for a wristband, as shown and described.

DESCRIPTION

FIG. 2 is a front elevational view of a wristband showing my new design;

FIG. 2 is a rear elevational view;

FIG. 3 is a top plan view, the bottom plan view being a mirror image;

FIG. 4 is a left side elevational view;

FIG. 5 is a right side elevational view; and,

FIG. 6 is a perspective view, the broken line showing of a hand and wrist being for illustrative purposes only and forms no part of the claimed design.

FIG. 1

FIG. 2

FIG. 3

FIG. 4

FIG. 5

UNITED STATES PATENT AND TRADEMARK OFFICE
